UNITED STATES PATENT OFFICE.

JAMES D. DOUGLAS, OF DETROIT, MICHIGAN.

PORTFOLIO.

Application filed October 20, 1926. Serial No. 142,824.

It is an object of this invention to provide a portfolio having two cover members united at their inner ends by a connecting portion, and a binder support mounted on one of the 5 cover members usually substantially at right angles to the said connecting portion so that a binder adapted to hold leaves therein may be readily engaged with or disengaged from the support.

10 Another object of the invention is to provide a flexible element secured both to the binder support and to one of the cover members of a portfolio so that the binder and its support may turn at varying angles to the 15 cover member as the leaves in the binder are turned.

A further object of the invention is to 20 provide a portfolio having means for preventing the binder slipping down below a predetermined position in its support when the latter is mounted on one cover member of a portfolio both cover members of which are adapted to form the inclined sides of a stand having its apex at the connecting portion 25 between the inner ends of said cover members.

Other objects and advantages of the invention will be apparent from a consideration of the following description in connection with which it will be noted that where- 30 as the invention is described and shown in conjunction with a portfolio having cover members adapted to open outwardly until their outer surfaces face one another and the 35 said members form two inclined sides of a stand, it may be applied to any type of portfolio.

In the drawings:

Figure 1 illustrates a portfolio having a 40 binder support mounted on one of its cover members.

Figure 2 is another view of the portfolio showing the binder support, binder and leaves mounted in the latter.

45 Figure 3 shows the portfolio in use as a stand with the binder support, binder and leaves in the latter.

Figure 4 is a partial view showing one form of binder.

50 Figure 5 shows a binder support to receive the binder shown in Figure 4, and part of the cover member to which the binder support is flexibly attached.

Figure 6 is a section on the line VI—VI of 55 Figure 5.

Figure 7 shows a modified form of binder support, and

Figure 8 is a modified form of binder intended for insertion into the support shown in Figure 7.

In the drawings, 1 and 2 designate cover members united at their inner ends as by a connecting portion 3. To the cover member 2 and preferably substantially parallel with its margin 9 one end 10 of an element 11 is secured, on the opposite end 14 of the element 11 a binder support 15 (or 15^a) is attached as by a rivet 16 (or 16^a), and intermediately of its length the element has a flexible portion 12 of such length as to permit the end 14 and the binder support 15 (or 15^a) thereon to turn about the cover member 2 as the leaves 5 in the binder 17 (or 17^a) are turned.

In Figure 5 the element 11 is shown so secured to the cover member 2 that its end 14, when substantially in line with its cover member, projects beyond the margin 9 of the latter, but when turned substantially at right angles to its cover member the said end 14 and the binder support 15 extend substantially in line with the margins 9 and 9^a of the cover members 2 and 1 respectively.

In Figure 7 the element 11 is mounted in such position on the cover member 2 that when the end 14 lies substantially flat against the said cover member its outer margin substantially coincides with the margin 9. Obviously wider leaves may be utilized if the binder support is mounted as in Figure 5 than if as shown in Figure 7, but the construction shown in Figure 7 affords greater protection to the end 14 and its binder support 15^a particularly when no binder is mounted therein.

Referring again to Figures 4 and 5, the binder support 15 has inturned margins 18 which form guides for the lateral projections 19 on the binder 17, and the lower end 20 of the binder, when in position, rests against a projection 21 located towards the lower end of the support 15. When several binders are provided, any one of which may be inserted into the portfolio for display purposes, it is sometimes advisable to do away with the projections 19. In that event the construction shown in Figures 7 and 8 may be utilized. The margins 18^a of the binder support are upturned to act as guides for the sides of the binder 17^a and the latter

has pins 22 with enlarged heads 22^a projecting outwardly therefrom. These pins cooperate with catches 23 on the support 15^a which have enlarged openings 23^a at their 5 upper ends to receive the heads 22^a before the binder is lowered into position.

To one of the cover members 2 a flexible portion 4 of sufficient length to fold around one edge of the leaves 5 is attached. At the 10 other end of the flexible portion 4 is a flap 6 which is in turn secured to an extension piece 7 by a joint 8. The cover member 1, the flap 6 and the extension piece 7 are provided with fasteners 24 so that the portfolio 15 may be secured either in closed position or 15 in such position as to form a triangular stand as indicated in Figure 3.

It will be noted that both methods herein shown for holding binders in position in 20 their supports are designed to retain them primarily in a vertically inclined position since the binder holding means is usually employed in portfolios of this nature. It is, however, apparent from the foregoing that 25 portfolios the cover members 1 and 2 of which lie outstretched may also be provided with such binder holding means.

While in the foregoing the preferred embodiments of the invention have been described and shown, it is understood that the construction is susceptible to such modifications as fall within the scope of the appended 30 claims.

What I claim as my invention and desire 35 to secure by Letters Patent is:

1. In a portfolio, the combination of two cover members flexibly connected at their inner ends, a binder support flexibly mounted on one of said cover members substan-

tially at right angles to the inner end of said 40 cover member, and a binder removably engaged with said binder support.

2. In a portfolio, the combination of two cover members flexibly connected at their inner ends, an element secured by one side 45 to one of said cover members substantially at right angles to the inner end thereof, a binder support attached to the other side of said element, said element being flexible intermediate of its width, and a binder removably engaged with said support.

3. A portfolio comprising two cover members flexibly connected at their inner ends so that they may be opened until their outer surfaces face one another and the said cover members form two sides of a triangle, means for holding the cover members when so opened in spaced relation to one another, an element on one of said cover members extending substantially at right angles to the inner end of its cover member, a binder support flexibly mounted at the outer margin of said element, a binder removably mounted on said support, and means for preventing 60 said binder from slipping out of said binder support when the latter is in a vertically inclined position.

4. In a portfolio, the combination of two cover members flexibly connected at their inner ends, an element secured to one of said 70 cover members and extending substantially at right angles to the inner end thereof and being flexible along the outer margin of the cover member, a binder support mounted upon said element and a binder on said support.

JAMES D. DOUGLAS.
